DESIGN FOR A GAME BOARD

Marion A. Elliotte, Philadelphia, Pa.

Application November 15, 1932. Serial No. 46,099

Term of patent 7 years

To all whom it may concern:

Be it known that I, MARION A. ELLIOTTE, a citizen of the United States, residing at Philadelphia, in the county of Philadelphia and State of Pennsylvania, have invented a new, original, and ornamental Design for a Game Board, of which the following is a specification, reference being had to the accompanying drawing, forming part thereof.

The figure is a perspective view of a game board, showing my new design.

The device consists of a relatively deep block

having a plate superposed thereon adjacent one end with a central, longitudinal raised portion having windows for observation of scoring means, and another plate in the rear of the first plate having a substantially central, longitudinal row of scoring indicia with rows of peg openings parallel therewith and symmetrically arranged on opposite sides thereof.

I claim:

The ornamental design for a game board as shown and described.

MARION A. ELLIOTTE.
